UNITED STATES PATENT OFFICE.

EDWARD J. BALLUFF, OF CHICAGO, ILLINOIS, ASSIGNOR OF ONE-HALF TO HARRY A. FITZGIBBONS, OF CHICAGO, ILLINOIS.

AUTOMATIC CURRENT-CONTROLLING MECHANISM OR SWITCH.

Application filed September 23, 1921. Serial No. 502,753.

This invention relates to automatic electric current controlling mechanisms or switches and electrical devices operatively connected therewith, adapted to provide means for preventing the discharging or exhaustion of the storage battery, or the burning out or injury of the coil or resistance or other electrical devices or connections normally embraced in the same electrical circuit.

10 The principal object of the invention is to provide a simple, economical and efficient automatic electric current controlling mechanism or switch and electrical devices operatively connected therewith, adapted to prevent the wasteful or injurious discharging of the storage battery, or the burning out or injury to the ignition coil or resistance or other electrical devices or connections normally embraced within the same electrical circuit with a storage battery.

15 Other and further objects of the invention will appear from the following description and claims, and from an inspection of the accompanying drawings, which are made 20 a part hereof.

The invention consists in the features, combinations, details of construction, and arrangement of elements and parts herein described and claimed.

25 In the accompanying drawings:—

Figure 1 is a view in elevation of my improved automatic electrically actuated switch or current-controlling mechanism, showing an electro-magnet having an electrically actuated switch member upon or operatively connected with the armature, and also showing a thermostat or thermostatic element which acts to open and close the circuit which energizes the electromagnet to actuate said switch;

Fig. 2, is a view in side elevation of the mechanism shown in Fig. 1, and also showing a portion of an internal combustion engine cylinder provided with a spark plug, a storage battery, an ignition coil, make and brake mechanism, switch, and electrical connections forming a circuit embracing or adapted to normally embrace the battery, ignition coil, make and brake mechanism and connected elements as shown in said figure; and

Fig. 3 is a diagrammatic view showing my improved automatic electrically actuated switch or current-controlling mechanism, and the electrical devices and electrical cir-

cuits and connections with which said automatic switch or current-controlling mechanism is adapted to be operatively connected.

In constructing an automatic current-controlling mechanism or switch and electrical devices adapted to be embraced within an electric circuit with which such automatic current-controlling mechanism or switch is adapted to be operatively connected, I provide an electro magnet 1 which may be in the form of a bar magnet having a core 2 surrounded with a coil 3 of helically wound insulated copper wire or electrically conductive wire adapted to be connected with a battery 4 which may be a dry battery or a storage battery, although the latter is usually employed or other source of electric supply. The core 2 may be in the form of an ordinary iron bar having its bottom end or metallic base 5 fixed to and in contact with the metallic bottom angular end portion or arm 6 of a metallic yoke 7 having an upper yoke arm 8 disposed at an angle with respect to the upright main body portion of the yoke and in parallel relation to the bottom yoke arm 6. The upper yoke arm 8 extends across or over the upper end of the core 2, and is spaced apart with respect to said core; and the bottom metallic yoke arm 6 is fixed to a base 8¹ of suitable insulating material, such, for instance, as fibre or hard rubber, or any suitable insulating material having the required strength to support the parts mounted thereon in operative position upon a frame 9, which may be any desired suitable frame member of an automobile, or other suitable support. An inclosing casing 10 may be provided and removably mounted on the base 8¹, said casing being of suitable dimensions, and hollow so as to inclose and cover and protect the electromagnet and mechanism mounted on said base.

The coil 3 is wound around the core 2 between end plates or spool ends 11 and 12 of suitable insulating material supported at or near the opposite ends of the core 2 and between the yoke arms 6 and 8, the upper plate 11 of insulating material being spaced apart with respect to the upper arm 8 of the yoke, and the lower plate 12 of insulating material being mounted between the lower extremity of the coil 3 and the bottom yoke arm 6, and in position to support the coil. Although the electro-magnet 1 here shown and described above as a single bar magnet

is well adapted to serve the purposes for which it is intended to be used, it will be readily understood by those skilled in the art that any desired ordinary and well known form of electromagnet, such for instance as an ordinary horse-shoe electro magnet may be employed.

In the form of electro-magnet herein shown and described, however, the upper 10 extremity of the yoke 7 and the upper yoke arm 8 are formed in one integral piece of metal, and an opening 13 is provided in the upper portion of said yoke, through which extends a hinged upwardly and downwardly 15 movable armature 14. One end portion 15 of the armature extends through the said opening 13 in the yoke and is supported in hinged engagement with said yoke, said armature having lateral end shoulders 16 20 on opposite sides of the central endwise projecting portion 15 and adapted to engage the inner upright side face of the upright portion of the yoke 7; and depending or downwardly bent lugs or bosses 17 on the 25 hinged end of the armature project downward in engagement with the outer side face of the upright portion of the yoke 7. The armature is thus supported in hinged engagement with the yoke, and in position to 30 permit the opposite or swinging end portion or body of the armature to swing upward out of contact with the upper end of the core 2, and downward into contact with said core, as required. A spring 18, 35 which in this instance is a tension spring, has its upper end connected with the projecting end 15 of the armature, and its lower end connected with a suitable support, which may be in the form of a connecting pin 19 fixed to and projecting laterally from the outer side of the yoke 7. This spring is thus adapted to hold the armature normally in raised position out of contact with the upper end of the core 2, as 40 shown in Figs. 2 and 3. Mounted on and movable with, or adapted to be operated with or by means of the armature 14, is a metallic switch member or arm 20, which in this instance is in the form of a slightly 45 flexible thin brass plate secured to the armature by means of a securing screw or other suitable securing means, and having a thin sheet or strip of insulating material 21 interposed between said metallic switch arm 50 55 and the armature.

A metallic contact member or bar 22 is mounted upon a suitable support of insulating material, such, for instance, as the hard rubber or fiber plate 11 which forms the 60 end of the spool. The upper end or contact point 23 of this contact member or bar 22 is located adjacent to and on the under side of the outer swinging end 24 of the metallic switch arm 20, and is normally spaced apart 65 from or out of contact with said metallic

switch arm; and a contact member or contact point 25 is fixed to or supported upon and in contact with the metallic upper arm 8 of the yoke 7 and adjacent to and in position to be engaged by a contact member 70 or point 26 upon and in metallic contact with the metallic switch arm 20 on the armature 14, when said armature is in raised position, and when the core of the magnet is not energized.

From the foregoing description it will be readily seen that when the core 2 is energized so as to lower the armature 14 and switch arm 20, the contact 24 will be brought into contact with the contact point 23 on the 80 contact bar 22; and the contact 26 on the switch arm 20 will at the same moment be brought down out of contact with the contact point 25 on the upper end of the metallic yoke 7 or yoke arm 8. It is also obvious that at 85 all times when the core 2 of the magnet 1 is not energized, the armature 14 will be in raised position, and the contact 26 on the switch arm 20 will be in actual contact with the metallic contact point 25 on the upper 90 metallic yoke arm 8.

Mounted on a suitable support, such, for instance, as the insulated base 8¹ of the electro magnet 1, is a curved flexible thermostatic element or expansible and contractable 95 compound or laminated bar member 27, which may be formed of parallel connected strips or layers of iron and brass, the strip, bar or layer 28 of iron being on the outer side of the curve, and the strip or bar 29 100 of brass or similar metal having a greater coefficient of expansion than the strip 28, being on the lower or inner side of the compound bar as a whole, and on the inner side of the curve 30.

The compound thermostat bar 27 is wound with a spiral coil 31 of insulated metallic wire or electrically conductive material having one end 32 fixed in electrically conductive engagement with the compound thermostatic member or bar 27, at or near the outer free or movable end of said bar member 27; and the compound thermostatic bar 27 has one end fixed to an insulated support by means of a screw 32 or other suitable securing means. The opposite free or movable end of the compound thermostat bar member 27 is located adjacent to and normally out of contact with the contact bar member 22 already described, and is provided with a metallic contact member or point 33 adjacent to and adapted to be moved into and out of electrical contact with a metallic contact end or contact member 34 connected with or forming an integral part of the electrically conductive bar or contact member 22. The main body of the bar 22 is connected with the contact 110 115 120 125 130 34 by means of a projecting end portion or metallic connecting wire or other form

of conductor 35; and the contact member 23, already described, is connected with the bar 22 by means of a metallic connection in the form of a wire or other form of electrical 5 conductor 36. The conductor 36 may be integral with the body of the bar 22 or connected therewith in any suitable ordinary and well known manner.

From the foregoing description of the 10 thermostatic member 27 and its connections, it will be readily understood that when the compound bar member 27 is heated to a predetermined temperature by being subjected to the action of an electric current having 15 or exceeding a predetermined amperage or degree of intensity, passing through the coil 31, the compound bar 27 will thus be caused to automatically expand so as to force the metallic contact point 33 carried by the free 20 end of the bar 27 into electrical contact or electrically conductive engagement with the contact point 34 of the metallic bar 22 already described. And it is obvious that 25 whenever the amperage or intensity of the electric current passing through the coil 31 is reduced to or below such suitable predetermined amperage or intensity the compound bar 27 or expansible thermostatic member will thus be permitted to cool and 30 contract thereby causing the contact point 33 to be moved out of contact with the terminal or contact 34 already described.

My improved automatic current-controlling mechanism or "cut out" is shown herein 35 as applied to or operatively connected with the electric circuit or ignition system of an automobile or auto-motive vehicle, including a storage battery, induction coil, switch, and mechanically actuated make and break device 40 operatively connected with the cam shaft 40 of an internal combustion engine 37, all of which may be of any ordinary and well known or suitable form, and may be provided with an electric starter, including 45 an electric motor or dynamo, and may have an auxiliary circuit including a magnet suitably connected and adapted to operate in any desired ordinary and well known or suitable manner, and which, being well known in the art are not shown.

In the drawings (see Figs. 2 and 3) I 50 have shown an ordinary internal combustion engine 37, provided with one or more spark plugs 38. Embraced within the same circuit with storage battery 4 is a mechanically actuated make and break device 38 which comprises in its construction a movable make and break member or switch arm 55, which in the form shown is pivotally or reciprocatingly mounted, and adapted to move into and out of contact with a stationary contact member 41 which is grounded in any suitable manner, for instance, by means of a wire 64 or other suitable electrically conductive means. The movable or recip-

rocatory make and break member or movable switch arm and contact member 39 is provided with suitable insulation 41' which insulates it from its support or pivot 42; and said movable switch member 39 is operatively connected with and adapted to be operated by the cam shaft 40 of an engine, said cam shaft being provided with suitable cam mechanism 42' rotative with the shaft and in operative engagement with and insulated from the adjacent cam-engaging portion of the said movable or insulated make and break member 39, which is thus adapted to be moved into and out of contact with the grounded contact member 41, to 75 make and break any circuit connected with said movable or insulated member 39. The mechanically actuated make and break device 38 may, however, be of any desired ordinary and well known form adapted to be 80 operatively connected with the devices herein described.

In Figs. 2 and 3 of the accompanying drawings, is also shown diagrammatically an ignition coil 43 which may be of any ordinary or desired form, and comprises a primary coil 44, and a secondary or induction coil 45. The secondary coil 45 is connected with the spark plug or plugs 38 by means of a wire or conductor 46 leading from one extremity of the coil 45 to the spark point, the opposite terminal of the spark plug being grounded in the ordinary manner by means of a conductor 47 leading from said terminal to the ground 48. The opposite extremity of the secondary coil 45 is grounded in the ordinary manner by means of a conductor 49 connected with said coil and leading to the ground 50. (See Fig. 3.)

One pole of the storage battery 4 is 105 grounded in any desired ordinary manner, for example, by means of a conductor 51 connected with said pole of the battery and leading to the ground 52, as shown diagrammatically in Fig. 3. Or the conductor 51 may lead from the battery to a switch 52, the opposite terminal 53 of the switch being grounded by means of a conductor 54 leading from said terminal or contact to the engine frame or ground, as shown in Fig. 2. 110

As will be seen by reference to Fig. 3, however, the opposite pole of the storage battery is electrically connected with the compound metallic thermostatic bar 27 by means of an electric wire 55 connected with said pole of the battery and leading to the binding post 56, and an electric wire 57 leading from said binding post 56 to the end 58 of said thermostat bar 27. An electric wire 59 leads from one extremity of the thermostat coil 31 to the contact member 26 on the hinged armature 14; and an electric conductor 60 leads from the metallic contact member 25 on the upper yoke arm 8 of the electro-magnet 1 to the binding post 61, 130

which is in turn electrically connected with one of the terminals of the primary coil 44 or ignition coil 43 by means of an electric conductor 62.

5 The opposite extremity of said coil 44 is connected with a corresponding make and break member, for instance, any one or more of the movable or insulated make and break members or contacts 39, by means of an 10 electric conductor 63; and the corresponding stationary make and break member 41 of the make and break device 38 is grounded in any ordinary manner, by means of an electric conductor leading therefrom to the 15 ground. The conductors 64 and 51 are thus electrically connected and in the same battery circuit. (See Fig. 3.)

From the foregoing description, it is obvious that, the contacts 33 and 34 being separated or in circuit breaking position, and 20 the engine in operation, as when the car is running, the battery circuit, or circuit of the electric current will be from the battery 4 through conductor 55, binding post 56, 25 wire 57, connection 58, thermostat bar 27, connection 32, thermostatic coil 31, wire 59, contact 26 on armature 14, contact 25 on upper yoke arm 8 of electro-magnet 1, conductor 60, binding post 61, electric conductor 30 62, ignition coil 43, or primary winding 44 of said ignition coil, through electric conductor 63, movable member or contact members 39 of the make and break device 38, and stationary make and break member or members 41 and conductor 64 to the ground 52', and from the ground through electric conductor 51, to the battery 4.

It is also obvious that, whether the engine is running or standing still, with the make 40 and break members 39 and 41 in contact, as illustrated in Fig. 3, and with the contacts 33 and 34 separated or in circuit-breaking position, and all of the parts as shown in said figure, the electric circuit in 45 which the storage battery 4, ignition coil 43, thermostat coil 31, and make and break members 39 and 41 are encased, will be as above described.

It will also be readily understood by those 50 skilled in the art, that whenever the electric current passing through the thermostat coil 31 and through the circuit above described, reaches or exceeds an amperage or intensity sufficient to heat the compound bar or thermostatic member 27 to a temperature sufficient 55 to cause said member 27 to expand so as to bring the contact 33 in contact with the terminal or contact member 34, a direct circuit will be closed or formed which will 60 pass through or embrace the coil 3 of the electro-magnet 1, and energize the core 2 of said electro-magnet—one extremity of said coil 3 being electrically connected with the contact 34 by means of the electric conductor or wire 35 already described, and

an electric conductor 65 leading from said extremity of the coil 3 to said wire 35, and the other extremity of said coil 3 being connected with an electric conductor or wire leading to binding post 67 to which is connected 70 an electric wire 68 leading from said binding post to a corresponding make and break member or members 39 of the make and break device 38 already described. The movable make and break member or members 39 are adapted to be moved into and out of contact with the corresponding stationary make and break member or members 41, connected with the conductor 64 which is grounded as already described. 80 The shunt circuit thus formed or closed, and which acts to energize the coil 3 of the electro-magnet 1, with the contacts 33 and 34 in contact or in circuit closing position, is as follows:

Through storage battery 4, conductor 55, binding post 56, electric conductor 57 connection 58, compound thermostat bar 27, closed contacts 33, 34, electric conductor 35, wire 65, electro-magnet coil 3, wire 66, binding post 67, electric wire 68, movable make and break member or members 39, engaged stationary make and break member or members 41, conductor 64 to the ground, 52', and through conductor 51 from the ground to 90 the storage battery 4. The electric current thus caused to pass through the coil 3 of the electro-magnet 3, energizes the pole 2 of said electro-magnet, thus causing the free end of the armature 14 to be attracted and lowered into contact with the core 2, and acting to lower or move the contact 26 out of contact with the terminal or contact point 25 on the upper yoke arm 8 and breaking the circuit between said contacts 25 and 26, and simultaneously causing contact 24 on the movable switch arm 20 on armature 14 to be moved downward into electrically conductive engagement with the contact 23 on the contact bar 22.

With the contacts 23 and 24 thus in contact or closed circuit-making position, and the contacts 25 and 26 out of contact or in circuit-breaking position, and with the contacts 33 and 34 temporarily and for a short 115 time only in contact or circuit-closing position, as they are temporarily or momentarily until the compound thermostat bar 27 is allowed to cool and contract so as to withdraw the contact member 33 out of contact with 120 the contact point 34, it is plain that an electric circuit is formed which passes through the contacts 23 and 24 which are held in contact by reason of the armature being held down by the energized core; 125 and the said circuit thus formed passing through the contacts 23 and 24 continues even after the contacts 33 and 34 are separated by the cooling of the thermostat bar 27, and is as follows, so long as the electro- 130

magnet coil and core continue to be energized and the armature remains in lowered position so as to hold the contacts 25 and 26 in open or circuit breaking position.

5 From the storage battery 4 through conductor 55, binding post 56, wire 57, connection 58, thermostat bar 27, connection 32, thermostat coil 31, electric wire 59, lowered contact member 26 on armature 14, switch arm 20 on armature 14, contact 24, engaged contact 23, conductor 36, electric wire 65, electro-magnet coil 3, wire 66, binding post 67, wire 68, make and break members 39 and 41 in contact with each other, electric 70 conductor 64 to the ground, and from the ground through wire 51 to the storage battery 4. The circuit last above described will continue so long as the engine or motor remains out of operation or stationary, with 75 the make and break members 39 and 41 or any of them in contact, so as to enable a closed circuit to continue as above described, through the coil 3 of the electro-magnet and through the engaged contacts 23 and 24 thus held in contact by the lowered armature 14 which is attracted by the energized core 2. The contacts 25 and 26 being thus held separated or in circuit-breaking position, it is plain that no electric current is permitted 80 to pass through the ignition coil 43, and that injury to the said coil while the parts remain as last above described, or while the engine is standing still, and all possibility of burning out the coil or resistance, is thus 85 prevented.

From the foregoing description it is evident that the circuit last above described passes through or embraces the armature-actuated switch arm 20 and contacts 23 and 24 of the automatic electrically actuated circuit breaker, and through the coil 3 of the electro-magnet 1 and the insulated member 39,—which in this instance is the movable member of the automatic mechanically actuated make and break device 38—and through the grounded or stationary make and break contact member 41 and wire 64 or other electric conductor to the ground, and passes through or embraces within the circuit the 90 storage battery, and the connected thermostatic expansible bar member and thermostatic coil, and thus energizes the core 2 of the electro-magnet 1, causing said core to attract the armature 14 and break the contact between the contact members 25 and 26 thus breaking the circuit to the induction coil 43. Said circuit thus embraces all of said electrically connected elements except the induction coil, but does not embrace the 95 induction coil. And although said circuit embraces the armature actuated switch member or arm 20 and contacts 23, 24, and 26 of the electrically actuated automatic circuit breaker, it does not embrace the contact member 25 and connected wires 60 and 62

leading to the terminal of the primary winding of the induction coil 43. (See Fig. 3, showing the position of the various elements just before the last mentioned circuit through the contacts or circuit-breaker 70 members 23 and 24 is closed by the heating of the thermostatic coil to or beyond a predetermined temperature sufficient to expand the thermostatic expansible bar 27 to cause a contact between thermostatic contact members 33 and 34 which would close the circuit acting to energize the electro-magnet.)

From the foregoing it will be readily understood that my improved "cut-out" or automatic current-controlling mechanism is 80 adapted to act automatically not only to break the battery circuit in which the ignition coil is normally embraced when the engine and the ignition system controlled by my improved automatic cut-out are in operation, so as to cut out the induction coil or ignition coil and thus prevent injury to the said induction coil when the engine is standing still or not in operation—for instance, when the engine has been left standing still 85 or not in operation, but with the ignition switch accidentally left closed, as it is liable to be in practice through carelessness or oversight of the operator, or otherwise, in which event the parts will be in the position shown 90 in Fig. 3 of the drawings, with the induction coil embraced in the closed battery circuit just as it would likewise be embraced in the same circuit with the battery when the engine is in operation but with the movable 95 make and break member 39, of course, acting to rapidly and continuously but alternately make and break the circuit when in operation—but that my improved safety device or automatic "cut-out" is also adapted 100 to automatically restore the circuit in which the induction coil and battery are embraced to normal or initial closed circuit forming operative position, without the necessity of providing or operating any separate or distinct restoring switch, electric button, or other or similar device whatsoever, and without requiring any attention from the operator to restore the mechanism herein described, or any part thereof to initial or 105 normal operative position.

On the contrary, the closing of the original circuit embracing the storage battery and induction coil as well as the thermostatic device and mechanically actuated make and break device and the ordinary switch, and the restoration of all of the parts to the position in which they are shown in Fig. 3, or normal operative position, with the electro-magnet cut out from the battery circuit, 120 but adapted to be again automatically connected with the expansible thermostatic device whenever the latter shall become heated to or beyond a predetermined temperature 125 and expanded by the building up of the elec- 130

6

tric current to or beyond a suitable normal or predetermined degree of intensity which, if exceeded would be liable to cause injury to the storage battery or to the induction coil 5 or resistance, is all accomplished automatically and without any attention of the operator or any act on his part other than the mere act of starting the engine in the ordinary manner. The first rotation of the 10 shaft 40 in the starting of the engine in the ordinary manner, will cause the movable make and break switch arm or contact member 39 to be separated from the contact member 41 and break the circuit passing through 15 the coil 3 and closed contacts 23 and 24 of the automatic electrically actuated circuit breaker device or electro-magnet 1, thus permitting the armature 14 to be raised by the automatic action of the armature-actuating 20 spring 18 already described, thereby bringing the armature-actuated switch arm 20 and the contacts 25 and 26 into circuit closing position, so as to form a circuit embracing the storage battery, the thermostatic device, the ignition or induction coil, and the 25 mechanically actuated make and break device, and the ordinary ignition switch, as shown in Fig. 3, in which the electrically actuated automatic circuit breaker mechanism 30 or electro-magnet is cut out, or separated from the battery circuit.

It will be readily understood by those skilled in the art that the electric current normally employed in the battery circuit embracing the induction coil when the engine and electrical devices are in operation is of relatively low amperage, but is liable to build up in intensity to an amperage which would burn out or injure the coil or resistance,—for instance, when the engine is stopped and permitted to remain idle or out of operation, with the ignition switch left closed accidentally or otherwise, so that the circuit embracing the storage battery and induction coil is closed as shown in Fig. 3. For instance, a current of from four to six amperes when the engine is not in operation, may quickly drop to one or two amperes immediately following the starting of the engine; and the current may again build up to an intensity of four to six amperes or higher when the engine is allowed to stand still or out of operation with the circuit closed as shown in Fig. 3. The thermostatic device 55 is adapted to remain out of contact with the contact 34 when in a relatively cool contracted condition; but is so constructed that the expandible thermostatic bar member 27 will expand and come into electric contact with said contact member 34 when in a relatively heated and expanded condition due to the resistance afforded by the thermostatic or heating coil 31 and the passage of a current at or in excess of a predetermined maximum 60 intensity, for instance a current which has

been permitted to reach or exceed an intensity of six amperes or thereabout, or any desired predetermined maximum amperage, thus causing the automatic electrically actuated circuit breaker comprising the electro-magnet 1 to break the circuit and cut out the induction coil, thus preventing injury to the coil by the building up of the electric circuit beyond such predetermined maximum intensity, and also preventing the storage 70 battery from becoming exhausted; and enabling the entire device to be restored automatically and without requiring any attention from the operator, but by the mere starting of the engine in the ordinary manner, as already described.

The making and breaking of the circuits between the contacts 33 and 34, and at the circuit breaker contacts 23 and 24, and contacts 25 and 26 is accomplished without any undesirable sparking, as the potential is comparatively low and very nearly uniform at both the thermostatic make and break device and the electrically actuated circuit breaker or armature-actuated contacts.

85 A motor or generator 65 is connected in parallel with the storage battery in the usual manner in such devices, and is adapted to charge the battery, and to be operated in the ordinary manner familiar to those skilled in the art.

90 It is obvious that the electrically actuated circuit breaker comprising the electro-magnet 1 and the make and break or switch mechanism operated thereby, may be connected with any suitable part of the circuit on either side of the thermostatic device, and between said thermostatic device and the battery or the coil; and it is also obvious 100 that there may be other modifications and reversals of parts without departing from the spirit of my invention. For instance, the thermostatic coil and the expandible thermostatic curved bar may be mounted in any desired position, upright or otherwise, 105 and the storage battery may be connected directly with the thermostatic coil instead of with the thermostatic expandible bar, the bar being connected directly with the terminal of the primary of the induction coil instead of with the battery. These and other obvious modifications will be readily apparent to those skilled in the art. And I 110 do not confine myself to the exact construction or arrangement of parts as herein shown and described, otherwise than as set forth in the claims.

115 I claim:

120 1. In a mechanism of the class described, 125 the combination of a battery, an induction coil, a mechanically actuated make and break device connected with one of the terminals of the induction coil, an expandible metallic thermostatic member adapted to be electrically connected with the battery, 130

- 1 a thermostatic heating coil connected with
2 said expansible thermostatic member, and
3 means forming an electrical connection be-
4 tween the thermostatic heating coil and a
5 terminal of the induction coil, all adapted
6 to be embraced within the same electric
7 circuit, and an automatic electro-magneti-
8 cally actuated circuit breaker connected
9 with said mechanically actuated make and
10 break device and adapted to be connected
11 with said circuit for breaking the same said
12 automatic circuit breaker comprising auto-
13 matically actuated means adapted to auto-
14 matically close and restore said circuit.
15 2. In a mechanism of the class described,
16 the combination of a battery, an induction
17 coil, a mechanically actuated make and
18 break device connected with one of the ter-
19 minals of the induction coil, an expansible
20 metallic thermostatic member adapted to be
21 electrically connected with the battery, a
22 thermostatic heating coil connected with said
23 expansible thermostatic member, and a cir-
24 cuit breaker comprising electro-magnetical-
25 ly actuated relatively movable contact mem-
26 bers connected with said thermostatic
27 heating coil and said induction coil, respec-
28 tively, and adapted to automatically break
29 an electric circuit embracing all of said
30 elements, said automatic circuit breaker
31 comprising automatically actuated means
32 adapted to automatically close and restore
33 said circuit.
34 3. In a mechanism of the class described,
35 the combination of a battery, an induction
36 coil, a make and break device connected
37 with one of the terminals of the induction
38 coil, an expansible thermostatic member
39 electrically connected with the battery, a
40 thermostatic heating coil connected with
41 said expansible thermostatic member, and
42 means forming an electrical connection be-
43 tween the thermostatic coil and an oppo-
44 site terminal of the induction coil, said con-
45 necting means comprising an automatic
46 electro-magnetically actuated circuit break-
47 er adapted to automatically break an elec-
48 tric circuit embracing all of said elements,
49 said automatic circuit breaker comprising
50 automatically actuated means adapted to
51 automatically close and restore said circuit.
52 4. In a mechanism of the class described,
53 the combination of a battery, an induction
54 coil, a make and break device connected
55 with one of the terminals of the induction
56 coil, a thermostatic device comprising an
57 expansible thermostatic member and a heat-
58 ing coil operatively connected, means for
59 connecting one of the terminals of the ther-
60 mostatic device with the battery, means for
61 electrically connecting the other terminal
62 of the thermostatic device with a terminal
63 of the primary of the induction coil, and
64 an automatic electro-magnetically electrical-
65 ly actuated circuit breaker comprising rela-
tively movable switch members connected
with and adapted to be embraced within
the same electric circuit with all of said
elements, said circuit breaker comprising
means for automatically breaking said cir-
cuit by moving one of said switch members
to circuit-breaking position, and electrical-
ly actuated means for automatically restor-
ing said movable switch member to circuit
closing position, to close said circuit.
66 5. In a mechanism of the class described,
67 the combination of a battery, an induction
68 coil, a mechanically actuated make and
69 break device connected with one of the ter-
70 minals of the induction coil, a thermostatic
71 device comprising an expansible thermo-
72 static element, and a thermostatic coil con-
73 nected with said expansible thermostatic
74 element, means for electrically connecting
75 said thermostatic device with the battery
76 and with one of the terminals of the induc-
77 tion coil, a contact member adapted to be
78 electrically connected with the thermostatic
79 expansible member and with said mechani-
80 cally actuated make and break device, an
81 electro-magnetically electrically actuated au-
82 tomatic circuit breaker comprising coacting
83 relatively movable switch members adapted
84 to be embraced within the same electric cir-
85 circuit with all of said elements, and means
86 for electrically connecting said electric cir-
87 circuit breaker mechanism with said mechani-
88 cally actuated make and break device,
89 whereby said electrically actuated circuit
90 breaker is adapted to automatically break
91 said battery circuit and cut out the induc-
92 tion coil from said circuit, and said elec-
93 trically actuated circuit breaker is also
94 adapted to automatically close said circuit.
95 6. In a mechanism of the class described,
96 the combination of a battery, an induction
97 coil, a mechanically actuated make and break
98 device connected with one of the terminals
99 of the induction coil, a thermostatic device
100 comprising an expansible thermostatic ele-
101 ment and a thermostatic coil connected with
102 said expansible thermostatic element, means
103 for electrically connecting one of said ther-
104 mostatic elements with the battery, means for
105 electrically connecting the other one of said
106 thermostatic elements with one of the termi-
107 nals of the induction coil, an electro-mag-
108 netically actuated automatic circuit breaker
109 comprising co-acting relatively movable
110 switch members adapted to be embraced
111 within the same electric circuit with all of
112 said members, said electrically actuated cir-
113 cuit breaker having an electromagnet pro-
114 vided with a core-encircling coil adapted to
115 be electrically connected with said expansible
116 thermostatic member and with a source of
117 electric supply, and having an armature
118 operatively connected with one of said cir-
119 cuit-breaker switch members and adapted to
120 automatically move said circuit breaker
121 125
122 130

- switch member to circuit-breaking position to cut out said induction coil from said first-mentioned battery circuit, and means for automatically restoring said armature-actuated 5 circuit-breaker switch member to circuit-closing position to close said circuit embracing the storage battery, induction coil, thermostatic device and mechanically-actuated make and break device, and not embracing 10 said electromagnet.
7. In a mechanism of the class described, the combination of a battery, an induction coil, a mechanically actuated make and break device connected with one of the terminals 15 of the induction coil, a thermostatic make and break device comprising an expansible thermostatic member and a thermostatic heating coil connected with said expansible thermostatic member, means for connecting 20 said thermostatic members with the battery and with the induction coil respectively, said connecting means comprising an electromagnetically actuated circuit breaker, and means for electrically connecting said circuit 25 breaker, said automatic circuit breaker comprising automatically actuated means adapted to automatically close and restore said circuit with said mechanically actuated make and break device.
- 30 8. In a mechanism of the class described, the combination of a battery, an induction coil, a mechanically actuated make and break device electrically connected with one of the terminals of the induction coil, an expansible 35 thermostatic member adapted to be electrically connected with one of the terminals of the battery, a thermostatic coil connected with said expansible thermostatic member, and means forming an electric connection 40 between the thermostatic coil and a terminal of the induction coil, all adapted to be embraced within the same electric circuit, said circuit having a pair of co-acting relatively movable circuit-breaker contact members 45 embraced therein, an electro-magnet provided with an armature operatively connected with one of said last-mentioned circuit-breaker contact members, and electrical circuit-forming means connected with and 50 embracing the coil of said electro-magnet and provided with a contact member connected with said electro-magnet coil and adapted to be electrically connected with said expansible thermostatic member when 55 the latter is in an expanded heated condition.
9. In a mechanism of the class described, the combination of a battery, an induction coil, a mechanically actuated make and break device electrically connected with one of the 60 terminals of the induction coil, an expansible thermostatic member electrically connected with one of the terminals of the battery, a thermostatic coil connected with said expansible thermostatic member, connecting means 65 forming an electrical connection between the thermostatic coil and a terminal of the induction coil, said connecting means forming a circuit comprising a pair of co-acting relatively movable circuit-breaker contact members embraced within the same electric circuit with all of said elements, an electro-magnet provided with an armature operatively connected with one of said last-mentioned circuit-breaker contact members, for making and breaking said circuit, and electrical circuit-forming means connected with said first-mentioned mechanically actuated make and break device and with the coil of said electro-magnet, and comprising a contact member connected with the magnet coil and adapted to be electrically connected with said expansible thermostatic member when the latter is in a heated expanded condition.
10. In a mechanism of the class described, the combination of a battery, an induction coil, a mechanically actuated make and break device electrically connected with one of the terminals of the induction coil, an expansible thermostatic member electrically connected with one of the terminals of the battery, a thermostatic coil connected with said expansible thermostatic member, connecting means forming an electrical connection between the thermostatic coil and a terminal of the induction coil, said connecting means comprising a pair of relatively movable co-acting circuit-breaker contact members embraced within the same electric circuit with all of said elements, an electro-magnet provided with an armature operatively connected with one of said last-mentioned circuit-breaker contact members, for making and breaking said circuit, electrical circuit-forming means connected with said first-mentioned mechanically actuated make and break device and with the coil of the electro-magnet, and comprising a contact member connected with the magnetic coil and adapted to be electrically connected with said expansible thermostatic member when the latter is in a heated expanded condition at a predetermined temperature, and disconnected when said thermostatic member is in a relatively colder contracted condition, and means for closing an electrical circuit embracing the storage battery, electro-magnet coil and said first-mentioned mechanically actuated make and break device, and the thermostatic coil and expansible thermostatic member and not embracing the induction coil.
11. In a mechanism of the class described, the combination of a storage battery, an induction coil, a mechanically actuated make and break device electrically connected with one of the terminals of the induction coil, an expansible thermostatic member electrically connected with the storage battery, a thermostatic coil connected with said expansible thermostatic member, connecting means forming an electrical connection between the

thermostatic device and the induction coil and provided with an electrically actuated circuit breaker connected with and adapted to make and break an electrical circuit embracing all of said elements, means for holding said circuit-breaker mechanism in circuit-breaking position, and automatic restoring means adapted to automatically restore the circuit-breaker mechanism to circuit closing position.

12. In a mechanism of the class described, the combination of a battery, an induction coil, a mechanically actuated make and break device electrically connected with one of the terminals of the induction coil, an expansible thermostatic member electrically connected with the battery, a thermostatic coil connected with said expansible thermostatic member and adapted to be electrically connected with one of the terminals of the induction coil, all forming a circuit in which all of said elements are embraced, automatic circuit-breaker mechanism comprising a movable switch member and a co-acting contact member connected with said electric circuit, said movable switch member being movable into and out of contact with said co-acting contact to make and break such circuit, an electro-magnet electrically connected with said first-mentioned mechanically actuated make and break device, and adapted to be electrically connected with said thermostatic expansible member when the latter is in heated expanded condition, said electro-magnet having an armature operatively connected with said movable switch member, for automatically actuating the same to make and break said electric circuit, and electrically conductive means adapted to be electrically connected with the electro-magnet coil and with said movable switch member and acting to close a circuit embracing said storage battery, thermostatic device and said first-mentioned mechanically actuated make and break device, and not embracing the induction coil when said movable switch member is out of contact with its first-mentioned co-acting contact member, and means for automatically restoring said movable switch member of the electrically actuated circuit breaker mechanism to initial circuit-closing position.

13. In a mechanism of the class described, the combination of a battery, an induction coil, a mechanically actuated make and break device electrically connected with one of the terminals of the induction coil, an expansible thermostatic member electrically connected with the battery, a thermostatic coil connected with said expansible thermostatic member and adapted to be electrically connected with one of the terminals of the induction coil, all forming a circuit in which

all of said elements are embraced, an electro-magnetically actuated circuit breaker normally connected with the thermostatic coil and with one of the terminals of the induction coil and adapted to make and break an electric circuit embracing all of said elements, spark-plug mechanism connected with the secondary coil of the induction coil, means for holding said circuit breaker mechanism in circuit-breaking position, and automatic restoring means electrically connected with said first-mentioned mechanically actuated make and break device and with a movable switch member of the electrically actuated circuit breaker mechanism, and adapted to automatically restore said circuit-breaker mechanism to circuit-closing position.

14. In a mechanism of the class described, the combination of a storage battery, an induction coil, a mechanically actuated make and break device electrically connected with one of the terminals of the induction coil, an expansible thermostatic member electrically connected with the storage battery, a thermostatic coil connected with said expansible thermostatic member, connecting means forming an electrical connection between the thermostatic coil and the induction coil, said connecting means comprising a contact member and a co-acting movable switch member movable into and out of contact with said contact member and adapted to make and break an electric circuit normally embracing all of said elements, an electro-magnet having an armature operatively connected with and adapted to move said movable switch member into and out of circuit closing position, electric circuit-forming means connected with and embracing the coil of said electro-magnet and adapted to be electrically connected with said expansible thermostatic member when the latter is in a heated expanded condition, and circuit closing means operatively connected with the armature of the electro-magnet and adapted to close an electric circuit embracing the storage battery, electro-magnet coil, the expansible thermostatic member and thermostatic coil, and said first-mentioned mechanically actuated make and break device, and not embracing the induction coil, said mechanically actuated make device acting to break said last-mentioned electric circuit and automatically release and permit the automatic restoration of the first-mentioned armature-actuated movable switch member of the electrically actuated circuit breaker mechanism to initial circuit-closing position.

Signed at Chicago, in the county of Cook and State of Illinois, this 19th day of September, 1921.

EDWARD J. BALLUFF.
